UNITED STATES PATENT OFFICE.

CHARLES A. SHANK, OF PHILADELPHIA, PENNSYLVANIA, ASSIGNOR OF NINE-TENTHS TO JAMES T. ELLISON, PHILIP H. CHARLES, JOHN H. HUDSON, AND CHARLES G. HENDERSON, JR., ALL OF SAME PLACE.

CAR STARTER AND BRAKE.

SPECIFICATION forming part of Letters Patent No. 352,782, dated November 16, 1886.

Application filed May 27, 1886. Serial No. 203,399. (No model.)

To all whom it may concern:

Be it known that I, CHARLES A. SHANK, a citizen of the United States, residing in Philadelphia, Pennsylvania, have invented certain 5 Improvements in Car Starters and Brakes, of which the following is a specification.

My invention relates to improvements in car-starters; and it consists of certain devices to enable the operator to assist in moving the 10 car forward on starting, or to put on the brakes when desired.

In the accompanying drawings, Figure 1 is a longitudinal section of part of a car, showing my improvements; and Fig. 2 is a sectional 15 plan view of the mechanism, showing the frame of the car in dotted lines.

A is the body of the car, constructed in the usual manner; B, the front axle, and D the rear axle, having the usual wheels.

20 On the axle B is a ratchet-wheel, E, and on an adjacent shaft, F, having its bearings in boxes f f on the frame above, is a ratchet-wheel, G. On this same shaft, F, is a winding-drum, g, to which is connected and on which 25 can be wound the brake-chain i. This chain passes over a pulley, i', on the rear brake-beam, I', and is connected to the front brake-beam, I.

Pivoted to a bracket, h, on the under side 30 of the front portion of the car, at j, is an operating-lever, J, to be manipulated by the driver. Two arms, M M', are pivoted to this hand-lever, the arm M being pivoted above the fulcrum j of the lever, at m, while the arm M' is 35 pivoted below, at m'. These arms have at their outer ends, in the present instance, double pawls n' n'', the upper pawl, n', being adapted to engage with the teeth of the ratchet-wheel G on the shaft F, while the pawl n'' is 40 adapted to engage with the teeth of the ratchet-wheel secured to the axle B when the pawls are depressed out of contact with the upper ratchet-wheel, G.

Two springs, P P, are secured to the body 45 of the car, and carry at their outer ends links p p, through which pass the arms M M'. These springs tend to keep the teeth of the arms M M' always up and in gear with the ratchet-wheel G.

50 A rock-shaft, S, having its bearings in blocks

secured to the frame of the car has an arm, s, which has a T-head resting on the upper face of the springs P, and attached also to this rock-shaft S is an arm, s', connected to a lever, T, by a link or rod, s''. This lever T is pivoted, in the present instance, to the shaft F, but may be attached to any portion of the car. The outer end of this lever is connected to an upright rod, U, having a head, u, and passing through a casing, t, in the floor of the car. 55 60

Between the lower portion of the casing and the head u is a spiral spring, t'. By pressing the foot on the head u the rock-shaft S is turned through the lever T, link s'', and arm s', so that the arm s presses down both springs 65 P P. The pawl-arms M M' are thus allowed to fall and engage with the teeth of the ratchet-wheel E on the axle B. When the foot is released, the springs P P lift the pawl-arms M M' back again to their normal position in 70 gear with the ratchet-wheel G.

When it is desired to apply the brakes, the lever J is moved backward and forward, so that the pawls on the arms M M' engage with the ratchet-wheel G and alternately turn it 75 partially around to wind up the brake-chain and apply the brakes to the wheels. When it is desired to start the car, the rod U is depressed to free the pawls from engagement with the ratchet-wheel G, and so release the 80 brakes, and also to allow the pawls to engage with the ratchet-wheel E on the axle, so that by then moving the lever J forward and backward the axle is turned to assist in starting the car. When the car has been fairly started, 85 the foot is taken off the rod U, and the arms M M' consequently lifted out of gear with the drum E and into gear with the drum G. By the use of two pawl-levers, M M', instead of one, the ratchet-wheels are operated at both 90 the forward and backward movement of the hand-lever J; but one pawl-lever may be used without departing from my invention.

I claim as my invention—

1. The combination of the brake-chain 95 drum of a car and ratchet-wheel with the car-axle having a starting ratchet-wheel, pawls to engage with either ratchet-wheel, a lever to reciprocate the pawls, and devices for throwing the arms or pawls into or out of gear with 100

either of the ratchet-wheels, substantially as set forth.

2. The combination of the car-axle having a ratchet-wheel and the brake mechanisms 5 with a ratchet-wheel controlling the brake mechanism, and a lever, J, having two pawl-arms, M M', pivoted one below and one above the fulcrum of the lever, and adapted to engage with either ratchet-wheel.

10 3. The combination of the car-axle having a ratchet-wheel, E, the brake-operating ratchet-wheel G, a pawl to engage with either of the ratchet-wheels, with a lever to operate the pawl, and a spring, P, adapted to hold the

15 pawl in gear with the brake ratchet-wheel G, and devices under the control of the operator for depressing the spring and allowing the

pawl to engage with the starting ratchet-wheel E, substantially as specified.

4. The combination of the car-axle having 20 a ratchet-wheel, and a brake-chain drum having a ratchet-wheel, with a pawl to engage with either ratchet-wheel, an operating hand-wheel therefor, and a rod, T, under the control of the operator's foot, to cause engagement 25 of the pawl with either ratchet-wheel, all substantially as specified.

In testimony whereof I have signed my name to this specification in the presence of two subscribing witnesses.

CHARLES A. SHANK.
